L. BONSIEUR

COMMUTATOR AND METHOD OF MAKING SAME

Filed Dec. 1, 1924

UNITED STATES PATENT OFFICE.

LE BONSIEUR, OF ELYRIA, OHIO, ASSIGNOR TO THE GENERAL PHONOGRAPH MANUFACTURING CO., OF ELYRIA, OHIO, A CORPORATION OF OHIO.

COMMUTATOR AND METHOD OF MAKING SAME.

Application filed December 1, 1924. Serial No. 753,411.

REISSUED

My invention relates to commutators and the method of making the same, and relates more particularly to the making of relatively small commutators such as are adapted for use upon small electrical motors which may be employed in electrical signal horns, for driving phonograph mechanisms and for driving toy machinery and the like, although my invention is not limited to such uses, but may be employed in connection with the making of commutators for larger motors for driving fans and for other purposes.

An object of the present invention is to simplify the making of commutators for electric motors and the like so that they can be more inexpensively manufactured in quantities.

Another object of the present invention is to accomplish the making of small sized commutators without the necessity of utilizing any considerable amount of hand operations incidental to the manufacture thereof.

Another object of my invention is to accomplish the making of small sized commutators of the aforesaid types which will be uniform when produced in large quantities and which will be rugged when completed and which will retain their ability to perform the commutating function in electric motors even when used for long periods under severe conditions of use.

Another object of the present invention is to economically produce in large quantities small-sized commutators in which the insulating medium may be applied as a plastic and which when congealed will efficiently hold together the commutator segments and resist deforming of the commutator by the single or conjoint effects of heat and mechanical shocks.

Other objects of my invention and the invention itself will become apparent as the description of certain embodiments thereof herein illustrated and described progresses.

Referring to the drawings forming a part of this specification—

Fig. 1 shows a side elevational view of a commutator constructed according to the principles of my invention by employment of the method described herein;

Fig. 2 shows the commutator of Fig. 1 viewed from the rear, the view being a plan view;

Fig. 3 is a transverse section taken on the line 3—3 of Fig. 1;

Fig. 4 is a longitudinal medial sectional view taken on the line 4—4 of Fig. 2;

Fig. 5 shows a plan view of a sheet metal stamping comprising the commutator segments extending radially from a common center and being joined together adjacent such center;

Fig. 6 shows an end view of the joined commutator segments of Fig. 5 subsequent to a bending operation in which the radially extending segments of Fig. 5 are so bent as to define an approximately cylindrical hollow cup;

Fig. 7 is a side elevation of the formed stamping of Fig. 6;

Fig. 8 is an end plan view of the stamping of Fig. 7 viewing the same from below as shown;

Fig. 9 is an end view of the commutator of Fig. 4 seen from below;

Fig. 10 is a longitudinal medial sectional view of a tool and die for compressing the congealing plastic insulating material contained within the cup-shaped stamping of Fig. 8.

In Fig. 1 I show a commutator completed and ready to be slipped onto a motor shaft by a tight driving fit thereon preferably, the commutator comprising a centrally disposed tube 2 preferably of soft steel and a plurality of commutator segments 3, 4, 5, 6, 7, 8 and 9 surrounding the said tube 2 and insulated therefrom by insulating material 10 which may be of any of a number of different compositions, but which I will describe herein as being of that material commonly known as bakelite. This bakelite insulating material extends entirely within the space between the tube 2 and the segments, and also extends between the segments near one end thereof and around the segments as shown at 11. The portion 11 of the insulating material joined to the inner portion 10 thereof forms a band or ring of insulating material outside the commutator segments and adjacent the terminals 12 of the segments, and prevents any portion of the solder or soldering fluxes employed in soldering electrical conductors to the terminals 12 from flowing out over the contact portions 13 of the segments.

The insulating material also protrudes be-

yond the segments at the other end in an insulating band portion 14, the bands 11 and 14 jointed integrally with the insulating material 10 making an integral cementitious insulating support for the commutator segments 3 to 9 inclusive and being formed of a composition material such as bakelite, will withstand considerable heat and severe mechanical blows, shocks and vibrations.

10 The steel tube 2 is preferably contained within the body of insulating material 10 particularly where the commutator is to be made in the larger sizes as it may be driven onto a motor shaft very tightly and without 15 the danger of thereby causing the body of the commutator to be expanded unduly and beyond its elastic limit to crack the commutator. The commutator, however, may be used with or without the tube 2, its use 20 being optional and desirable principally in the larger sizes of commutators.

The commutator of Figs. 1 to 4 inclusive is preferably formed from a single sheet metal stamping such as a stamping of brass 25 or copper, being cut in a form such as that shown in Fig. 5 wherein the commutator segments 3 to 9 inclusive are shown as extending radially from a common center whereat the stamping is preferably perforated as shown at 15 and the segments being joined together by a connecting ring of the stamping material shown at 16. The perforations 17 may be provided, their use being optional, but where provided as shown the 30 blank may be more easily bent adjacent such perforations, and the material may be cut away at such perforations somewhat more easily.

The ends of the segment portions are 40 preferably formed in the accepted shape for electrical terminals as shown at 12 comprising a hook portion 18 adapted to receive an electrical circuit conducting wire which may be soldered to the terminal 12 after 45 the commutator has been completed and placed on a motor shaft. The stamping as shown in Fig. 5 is then placed in a punch-press and in the manner usual for such pressing operations, the radially extending 50 arms of the stamping comprising the segments in the ultimate product are bent into substantially cylindrical form as shown in the figure, and the ring shaped joining portion 16 forming the bottom wall of the cup-shaped article so formed. The resultant integrally formed piece is illustrated in Figs. 55 6 to 8 inclusive which show respectively the article in end, plan, side elevational and opposite end plan views, the adjacent edges 60 of the so-called segment arms 3 to 9 inclusive may be machined at this stage of the operation by running a cutting saw between the segment arms. This machining operation, however, may be omitted as the 65 adjacent edges generally are sufficiently

regular and spaced that no machining is necessary.

The cup-shaped article is then placed in a die recess and filled with bakelite insulating material in preferably powdered form and the bakelite therein then heated and subjected to pressure by an advancing tool 19 compressing the heated material within the cavity 20 of the die 21, reference being had to Fig. 10 showing the die having the cavity 20 with a shelf portion 22 recessed from the surface 23 of the die and having a stepped portion 24 at the bottom of the cavity, the recess 24 and shelf 22 as well as the interior 25 of the cavity being filled with heated bakelite which while being congealed from plastic condition is subject to the pressure of a pressure tool 19 pressed downwardly over the ends 12 of the commutator segments and into intimate pressure creating contact with the body of insulating material congealing within the cavity.

The tool 19 receives the ends 12 of the so-called segments in an annular shaped recess on the bottom face of the tool, the depth of the recess being sufficient to clear the ends of the terminals 12.

After the commutator is thus formed it may be removed from the cavity of the die 21 and placed into a tool or clamp (not shown), while the cutting end of a bit or cutting tool (not shown) may be directed axially through the opening 15 of the commutator shell and then through the insulating material to produce the axial opening 95 through which the motor shaft, upon which the commutator is to be mounted, may be passed. A similar tool having a larger diameter may now be passed into the opening 100 thus formed so that the cutting edges of the bit will remove the joining portion or ring 16 whereby the segments 3 to 9 inclusive will be separated and electrically insulated one from the other as shown in Figs. 105 1 and 4.

The finished commutator is shown in Figures 1 and 4, and as therein shown comprises a plurality of commutator segments 3 to 9 inclusive, having contact surfaces 52, 116 each forming a portion of the complete cylindrical outer surface of the commutator, the insulating material 25 connecting all of the segments and holding them against dislodgement, filling the inner segmental 120 spaces and preventing the spacing between the segments becoming modified.

The axial bore of the commutator is made of such a size that the commutator will fit tightly on the end of a motor shaft making 125 frictional contact therewith and this frictional contact may be increased by knurling or otherwise roughening the motor shaft at the point where the commutator is forced onto it. I prefer, however, to solder the 130

electrical circuit conductors leading the motor armature windings to the terminals 12 of the commutator segments.

Having thus described my invention in 5 different embodiments, I am aware that the same may be practiced according to the principles of my invention, but according to methods departing colorably from the complete method herein described for 10 accomplishing the result of my invention and that the product of the method herein described may be produced by other methods, but such departures will be comprehended in the spirit of my invention and in the accompanying claims.

I claim:—

1. The method of making a commutator comprising a plurality of segments, consisting of cutting from sheet metal a piece 20 having radially extending arms joined at their inner ends, then bending the arms so as to approximately define a cylindrical cup, then in placing a plastic congealable insulating compound within the substantially 25 cup-shaped article thereby produced and permitting a portion of the compound to flow between the arms to form a band surrounding the arms but united thereto, and to the rest of the compound within the 30 arms, permitting the compound to congeal, and subsequently removing the portion of the sheet metal joining the inner ends of the arms.

2. A commutator having a plurality of segments, each of said segments comprising 35 an intermediate portion having an outer contact surface, the contact surfaces of the segments being so formed as to approximately define a cylinder, an end of each segment being turned inwardly, and a body 40 portion of cementitious congealable insulating material uniting and spacing the segments, said body portion having a bore axial to the segment contact surfaces, and an insulating band surrounding the segments at a 45 point adjoining their contact surfaces, said band being united firmly to the said insulating material body portion by connecting insulating material portions extending between the segments.

3. A commutator having a plurality of segments, each of said segments comprising 50 an intermediate portion having an outer contact surface, the contact surfaces of the segments being so formed as to approximately 55 define a cylinder, an end of each segment being turned inwardly, and a body portion of cementitious congealable insulating material uniting and spacing the segments, said body portion having a bore axial to the segment contact surfaces, and an insulating band surrounding the segments at a 60 point adjoining their contact surfaces.

In testimony whereof I hereunto affix my signature this 25th day of November, 1924.

LE BONSIEUR.
